[57] CLAIM

The ornamental design for a poly-V pulley, as shown or described.

DESCRIPTION

FIG. 1 is a perspective view, from the side and bottom, of a poly-V pulley according to my new design.

FIG. 2 is a bottom plan view thereof;

FIG. 3 is a side elevation thereof, being the same from all directions;

FIG. 4 is a top plan view thereof; and,

FIG. 5 is a section view taken along the line 5—5 in FIG. 2.

FIG. 1

FIG. 2

FIG. 3

FIG. 4

FIG. 5
